UNITED STATES PATENT OFFICE.

WALTER SPIES, OF NEW YORK, N. Y.

FOUNTAIN SEALING DEVICE.

Application filed November 7, 1922. Serial No. 599,583.

To all whom it may concern:

Be it known that I, WALTER SPIES, a citizen of Germany, and a resident of the city of New York, borough of Manhattan, 5 in the county and State of New York, have invented a new and Improved Fountain Sealing Device, of which the following is a full, clear, and exact description.

This invention has relation to sealing devices and has particular reference to an apparatus for melting and applying sealing wax to letters, packages, parcels or the like.

At the present time it is customary to melt the wax over a flame and apply the same 10 while in molten condition to the article to be sealed, and under this practice considerable time and labor is required in addition to the risk and hazard of fire. Furthermore under this practice the wax is wasted due 15 to the fact that a uniform application of the same is impossible and the superfluous wax tends to increase the cost of postage.

It is therefore an object of the present invention to eliminate the above recited objections by providing a device which efficiently and economically effects the application of sealing wax to the articles to be sealed, which device does away with the flame used in melting the sealing wax stick 20 by substituting an electric heating element therefor.

As a further object the invention contemplates a fountain sealing device which includes a manually controlled outlet and 25 which may be employed in the nature of a pencil for uniformly distributing and applying the wax to the article to be sealed.

As a still further object the invention contemplates a device of the character described 30 which is extremely simple in its construction, inexpensive to manufacture and which is thoroughly reliable and highly efficient in its purpose.

With the above recited and other objects 35 in view, the invention resides in the novel construction set forth in the following specification, particularly pointed out in the appended claims and illustrated in the accompanying drawings, it being understood 40 that the right is reserved to embodiments other than those actually illustrated herein to the full extent indicated by the general meaning of the terms in which the claims are expressed.

In the drawings—

Figure 1 is a perspective view of the seal-

ing device constructed in accordance with the invention.

Figure 2 is a longitudinal sectional view 60 therethrough.

Figure 3 is a cross sectional view taken approximately on the line 3—3 of Fig. 2.

Figure 4 is a fragmentary detail sectional view taken approximately on the line 4—4 65 of Fig. 3.

Figure 5 is a transverse sectional view taken approximately on the line 5—5 of Fig. 2.

Referring to the drawings by characters of reference, the device comprises a receptacle 10 which is provided with a lower conical wall 11 having a discharge or outlet opening 12 at its apex which also forms a valve seat with which a ball valve 13 coacts to close the same. The ball valve is 70 provided with a valve stem 14 which extends upwardly through the upper wall 15 of the receptacles and is provided with spaced enlargements or heads 16 which lie on opposite sides of the slotted portion 17 of the 75 arm 18 of a manipulating lever 19. The arm 18 is provided with downturned lugs 20 which fulcrum the lever for rocking movement. A pair of screws 21 extend through the arm 18 and have mounted between their heads 22 and the arm coil springs 23 which normally rock the arm 80 and lever to a position to effect the movement and seating of the ball valve 13 against the seat or discharge port 12 whereby the 85 receptacle is closed against the discharge of its contents. The upper wall 15 of the receptacle is provided with an upstanding internally threaded boss 24 which receives the lower externally threaded end 25 of a sleeve 90 26, which sleeve is surrounded by a tubular handle 27 spaced from the sleeve to provide an air chamber 28 between the same and the handle. The handle is further provided 95 with apertures 29 located adjacent its opposite ends to permit of the free circulation of air therebetween for preventing the heating of the handle. An electric heating element 30 surrounds the receptacle 10 and is 100 suitably connected by an extension cord 31 to an electric heat regulating fitting 32 from which a conduit 33 leads to the source of supply. A covering shell 34 is arranged 105 over the receptacle and the lower end of the handle to guard the heating element against 110 the contact of the same with the person of the user or the article which is being sealed.

The shell is provided with an inner lining of insulating material 35 and said shell is formed with a slot 36 through which the manipulating lever 19 extends.

5 Preferably the handle is provided adjacent its upper end with a bail 37 by means of which the device may be suspended from a suitable support such as the hooked upper end 38 of a standard 39 having a supporting 10 base 40.

In use and operation the sealing wax W in stick form is introduced to the handle through the sleeve 26. The current is then supplied to the electric heating element 30 whereby the receptacle 10 will be heated to melt the lower end of the stick of sealing wax and maintain the same in a molten condition in the receptacle 10. In sealing letters, packages, or other articles, the handle 15 27 is grasped and the device used in the nature of a pencil. To admit of the feeding of the wax through the discharge port 12, the manipulating lever 19 is pressed toward the handle thereby rocking the same against 20 the action of the springs 23 to unseat the ball valve 13 and permit of the discharge of the wax therefrom. The cutting off of the feeding of the wax is accomplished by releasing the lever, thus permitting the 25 springs 23 to seat the valve 13. The circulation of the air through the apertures 29 to the air space 28 tends to insulate the handle 27 from the sleeve 26, thus maintaining the handle cool during the use of the device. When not in use the device may be 30 suspended and supported from a hook or other supporting element substantially as illustrated. By using a device of this nature for applying sealing wax, it will be 35 found that a great economy is effected as well as reducing the fire hazard and saving both time and labor.

I claim:

1. In a fountain sealing device for receiving, melting and facilitating the application of sealing wax, a heated wax receiving and melting chamber having a conical bottom wall provided with a concentric circular opening and an internally arranged 45 manually controlled spherical valve projecting partially through and cooperating with said discharge port for respectively closing and opening the same and to constitute a point for the device around the surface of 50 which the molten wax flows, and by means of which it is applied to the article to be sealed.

2. A fountain sealing device including a receptacle for receiving and holding a 55 quantity of sealing wax, said receptacle having a conical bottom wall formed with a concentric circular discharge port, an electric heating element associated with the receptacle for melting and maintaining the 60 wax therein, in a molten condition, an in-

ternally arranged manually controlled spherical valve projecting partially through and cooperating with said discharge port to constitute means for respectively closing and opening said port and constituting a 70 point for said device when the valve is open, around the surface of which the molten wax flows and by means of which the wax is applied to the article to be sealed.

3. An apparatus for receiving, melting and facilitating the application of sealing wax sticks comprising a tubular handle member having an open upper end, an enlarged receptacle communicating with the lower end having a conical bottom wall provided with a circular axial opening, an electric heating element embracing said receptacle whereby a stick of sealing wax introduced through the open end of the handle member is melted and maintained in a molten condition within the receptacle by the heating element, and an internally arranged manually controlled spherical valve projecting partially through and cooperating with 80 said circular opening to close and open the same and to constitute a point for said device around the surface of which the molten wax flows and by means of which it is applied to the article to be sealed.

4. An apparatus for receiving, melting and facilitating the application of sealing wax sticks comprising a tubular handle member having an open upper end, an enlarged receptacle communicating with the lower end having a conical bottom wall provided with a circular axial opening, an electric heating element embracing said receptacle whereby a stick of sealing wax introduced through the open end of the handle member is melted and maintained in a molten condition within the receptacle by the heating element, and an internally arranged manually controlled spherical valve projecting partially through and cooperating with 90 said circular opening to close and open the same and to constitute a point for said device around the surface of which the molten wax flows and by means of which it is applied to the article to be sealed.

5. A fountain sealing device comprising a hollow head having a funnel shaped bottom wall provided with a circular concentric discharge port, a tubular upstanding handle member having communication therewith comprising inner and outer spaced concentric walls, the said outer wall having radial openings adjacent its upper and lower ends to permit of a circulation of air between said walls for cooling the handle, a heating element surrounding said head for melting 105

the contents and maintaining the same in a molten condition, a covering jacket surrounding and protecting the heating element, a ball valve within the funnel shaped bottom wall of the head and partially projecting therefrom when in open relation to the discharge port to constitute a point for the device around the surface of which the molten wax feeds and the remains of which is applied to the article to be sealed, means 10 connected with said ball valve for normally setting the same with relation to the discharge port, and a manipulating handle connected with said means and located adjacent the lower end of the device for unseating the ball valve with relation to the discharge port. 15

WALTER SPIES.
